FIG. 1

FIG. 2

FIG. 3

FIG. 4

FIG. 6

FIG. 5

FIG. 1 is a fragmentary perspective view of a wiring duct showing my new design;

FIG. 2 is a fragmentary perspective view thereof with the cover omitted for purpose of disclosure;

FIGS. 3, 4 and 5 are respectively fragmentary top, side, and bottom views thereof, with the cover omitted for purpose of disclosure; and

FIG. 6 is an end view thereof, with the cover omitted for the purpose of disclosure.

The duct is fragmentarily shown in FIGS. 1 and 2 and broken away in FIGS. 3, 4 and 5 to indicate indeterminate lengths.

I claim:

The ornamental design for a wiring duct, as shown and described.
